ELECTRIC CLOCK

Frank Davenall Norton, Cheadle, England, assignor
or of one-half to John Frederick William Stuart,
Withington, Manchester, England

Application December 12, 1938, Serial No. 245,327
In Great Britain December 15, 1937

7 Claims. (Cl. 58—38)

This invention relates to electrically actuated clocks and has for its principal object to provide a new or improved method of and means for actuating the chiming and/or striking mechanism.

- 5 According to the present invention an electric synchronous motor is provided which is adapted to impart continuous and regular motion to the hands through suitable gearing in known manner. Such gearing is adapted to impart, preferably 10 through an intermediate gear wheel, continuous and regular motion to one element of a separable clutch the other element of which is connected to a chime and/or striking drum, the slideable clutch element or associated part being formed 15 or adapted to function as a counter to govern the extent of the chimes and/or the number of strikes after the manner of a counting plate associated with a locking member actuated by or from the time indicating mechanism and also 20 adapted to impart the desired longitudinal movement to effect and maintain the clutch elements in operation until said locking member enters a notch or depression, so that the chime and/or striking drum are driven, directly through the 25 clutch, to the extent necessary to give the desired chime and/or strike without the necessity for racks, gathering pallets and snails or the like and attendant gearing.

According to another feature of the invention 30 the chimes mechanism is automatically set and maintained in correct synchronism with the time indication, by means of projections or arms on the tappet wheel or the like on the time element, the length of which are varied to vary 35 the movement of the interconnected mechanism controlling the chiming drum or barrel, and the surface of the latter or part interconnected therewith carrying projections or recesses arranged or adapted so as to only be engaged in correct 40 sequence to ensure that the cycle of movement of said drum or barrel always corresponds in each hour, to the cycle of movement of the time indication hands.

A convenient method is to provide a clutch 45 element connected to the chiming drum which is mounted so as to be capable of a sliding motion, said drum being formed with projections or recesses spaced apart at intervals corresponding to the amount of motion to be imparted to 50 said drum to effect a given chime, said projections or recesses lying within the path of a complementary recess or projection on a member movable under spring pressure or the like normally tending to move the parts together so that a 55 projection on one member engages a recess on

the other member to arrest the movement of the drum, said movable member being controlled by a rocking lever or the like adapted to impart motion thereto when actuated by a tappet wheel or the like rotated continuously and uniformly by the time indicating mechanism, said tappet wheel having teeth or projections shaped or spaced apart proportionately, relatively to each other, according to the time intervals of the chiming so as to free the drum at the required time interval, whereupon the complementary projections and recesses move out of register with each other and immediately upon the release of said rocking arm or the like the spring pressed member is free to exert itself to impart a sliding movement of the drum to couple the two elements of the clutch so that the chiming drum is revolved for a part rotary motion the length of which is determined by the interengagement of the next projection and recess thereon.

Assuming such drum to be used for chimes for the quarter hours then it is preferred to associate a separate disc or drum, constituting a counting plate to control or effect the hour strike. Said counting plate is also driven from the time indicating gear and has associated therewith the moving clutch element of a second clutch which is controlled in like manner to the first, and is preferably interconnected to the chiming drum to positively prevent rotational movement there- 30 of until said drum has finished a complete revolution. This is conveniently effected by providing a detent, one end of which engages the counting plate while the other end bears against a snail or cam forming part of or connected to 35 the quarter chiming drum so that the time indicating drive can move the counting disc which governs the movement of the hammer actuating pin-wheel only when the quarter hour drum has completed a full revolution thereby ensuring no 40 overlapping of the chime and strike.

In order to ensure that the chimes and/or striking mechanism shall be maintained in correct synchronism with the time indication the projections and/or length of arms on the tappet 45 wheel are varied to vary the extent of movement of the interconnected mechanism controlling the chiming drum, and the surface of the latter or part interconnected therewith carrying the projections or recesses is arranged so that they lie 50 in different planes or are otherwise adapted so as to only be engaged in correct sequence to ensure that the cycle of movement of said drum always corresponds in each hour, to the cycle of movement of the time indication hands. 55

The invention will be more particularly described with reference to the accompanying drawings wherein the same reference numerals or characters refer to the same thing or part throughout the several views and wherein:

Figure 1 is a diagrammatic front view of a clock showing the invention applied thereto only such parts of the clock necessary for a clear understanding of the invention being shown.

Figure 2 is an end elevation looking from the left hand side of Figure 1 and

Figure 3 is a corresponding view looking from the opposite end of Figure 1.

Figure 4 is an end elevation of the chiming drum detached.

Figure 5 is a detail view showing the gearing for setting the hands while

Figure 6 is a detail view showing in end elevation the counting plate for the hour strike and locking member therefor.

In carrying the invention into effect according to one convenient manner as illustrated an electric clock motor 1 with associated gearing coupled to the hour and minute hands 2 and 3 respectively is mounted on a clock frame provided with a dial 4 and meshing with said gearing is another gear wheel 5 or train of gears meshing with a gear wheel 6 formed in one with or rigidly connected to a clutch element 7 fixedly mounted on a spindle 8 journalled in the framework and having rotatably mounted thereon a drum 9 having projecting pins 10 for actuating the hammer trips 11 of which any desired number may be provided, usually four, (see Figure 2), for striking the quarter hour chimes, the series of pins 10 being arranged on the separate segments of the drum proportioned relatively to each other to give the correct chime for each quarter in known matter.

Said drum 9 has formed or attached thereto, at the end adjacent to the fixed clutch element 7, the complementary clutch element 12, said clutch being of any convenient type, for example a one way ratchet toothed clutch as shown, the barrel 9 being influenced by a spring 13 located on the spindle 8 between the two clutch elements normally acting to move the barrel outwards to separate said clutch elements.

The opposite end face of the drum 9 is provided with a series of recesses 14, one in each segment of the drum carrying the separate series of pins 10 to actuate the given chime, all lying in the same pitch circle in line with which is a peg 15 adapted to enter therein, said peg being mounted on one arm 16 of a bell crank lever 17 pivotally mounted on the frame at 18 normally acting under the pressure of the spring 19 to move the peg 15 into engagement with one of the recesses 14 on the barrel. The other arm 16a of the bell crank lever 17 is acted upon by one end of a rock lever 20 pivotally mounted at 21 on the frame with the other end lying in the path of a small or tappet wheel 22 rotated by the time gearing, said tappet wheel having four arms 23, of which three are of equal length whilst the fourth is of greater length for a purpose hereinafter explained.

The operation of the device is as follows; assuming the motor to be driving the gearing to move the hands, a like continuous rotary motion is imparted to the fixed clutch element 7, the movable element 12 forming part of the drum 9 being separated therefrom due to the interposed spring 13 having moved the barrel endwise, the frictional drive of the barrel due to said spring

being resisted due to the engagement of the peg 15 on the lever 16 with one of the recesses 14 in the barrel so that no rotation of the chiming barrel takes place.

Continuous rotation of the tappet wheel 22 is also taking place and one of the short arms 23 thereon tilts the lever 20 which in turn rocks the bell crank lever 17 to an extent such that immediately preceding the disengagement of said arm 23 from the end of the lever 20, that is to say, at or near the end of the time period, in this instance one quarter of an hour, the peg 15 is withdrawn from the recess, the barrel 9 then turning slightly, due to the frictional drive, through the spring 13, to move the respective recess 14 out of register with the pin 15 so that immediately the end of the rocking lever 20 falls off the tappet arm 23, the spring 19 retracts the bell crank lever 17 with the peg 15 bearing against the solid end of the barrel 9, said spring 19 overcoming the spring 13 so as to push said barrel along the spindle 8 until the clutch elements 12, 7 engage, when the predetermined part rotary movement of said barrel takes place, the longitudinal movement of the barrel moving the pins 10 into the path of the respective hammer trips 11, to cause the pins 10, 10 on the appropriate segment to actuate the gong hammers 24 which are carried from the respective hammer trips by the rods 25, said hammers striking the gong arms 26 as seen more particularly in Figure 1.

At the end of said part rotary movement, the barrel 9 is brought into position with the next recess 14 in register with the peg 15 which enters therein as said barrel immediately moves in the axial direction, due to the endwise pressure of the spring 13 so that the clutch elements 7, 12 separate while the peg 15 entering the recess 14 prevents further rotational movement of the barrel 9 until the next repeat operation, as governed by the next tappet arm 23.

Projections 27 on the barrel 9 are provided, one for each recess 14, adapted to engage a stop 28 on the frame to positively limit the turning movement of the barrel 9 due to friction and serving to move the respective recess 14 out of register with the peg 15, the barrel 9 being released or disengaged from the stops 28 when endwise movement thereof takes place to render the clutch 50 operative, as such endwise movement is sufficient to traverse the projections 27 clear of the stop 28.

The foregoing series of movements takes place for the first three quarter chimes but with the fourth quarter chime the long arm 23a on the tappet wheel 22 gives an increased motion to the rocking arm 20 and consequently to the bell crank lever 17 and peg 15 so that the latter is lifted clear of a raised stop 29 which is located on the barrel face behind the relevant depression 14 and which, (the stop 29) otherwise prevents the release and rotation of the chime barrel until the minute hand has completed the last quarter of any hour whereby the chimes are self adjusting and self correcting. If desired all the teeth 23 may be of varying length and additional stops 29 of correspondingly varied height be placed behind the respective recesses 14 but it is found that automatic rectifying means adapted to function once, if required, during each cycle of movement are quite sufficient for practical purposes.

To allow the hands to be manually set, independently of the motor or the chiming barrel, the drive from the motor pinion a^1 through the pinions a^2 , a^3 and a^4 is transmitted to the hands 75

by means of a one way drive comprising a ratchet wheel 30 (see Figure 5) the pawls 30^a for which are mounted on the said pinion 4^a while the ratchet wheel 30 is rigidly mounted on the shaft 5 which carries the minute hand.

The chiming barrel will therefore automatically set itself to the correct chime when the peg 15 engages the stop 29 as previously explained.

To strike the hours a second drum or disc constituting a counting plate 33 is provided which is also driven from the time indicating gear in like manner to the chiming drum. The continuously revolving clutch element 34 in this case is formed in one with a pinion 35 which is constantly in mesh with a pinion 5 permanently attached to the constantly revolving pinion 5 which meshes with the pinion 6 of the clutch element 7.

Said clutch element 34 is fixedly mounted on the spindle 36 journalled in the frame work and having rotatably mounted thereon the drum 37 to one end of which the counting plate 33 is secured, whilst at the other end the complementary clutch element 38 is secured, the barrel 37 and consequently the counting plate 33 being influenced by a spring 39 located on the spindle 36 between the two clutch elements, normally acting to move the plate 33 outwards to separate the clutch elements.

A second bell crank lever 40 pivotally mounted on the frame at 41 is provided with an arm 40^a having a pin 42 to engage slots 43 in the plate 33 and lock said plate against the frictional drive due to the spring 39. The other arm 40^b of the bell crank lever 40 is adapted to be depressed, 35 against the resistance of the spring 44, by a rocking lever 45 whose opposite end 46 is acted upon by a snail or cam surface 47 formed on or attached to the chime barrel 9 as seen more particularly in Figure 1.

40 The combined clutch element 38 and counting plate 33 have rigidly attached thereto a pinion 48 meshing with a pinion 49 rigid on a spindle 50 journalled in the frame and having the pin wheel 51 attached thereto, the gear ratios of the pinions 48 and 49 constituting multiplying gear to impart increased rotary motion to the pin wheel.

The hour hammer 52 is provided with a trip end or pallet 53 lying in the path of the pins or teeth 51^a of the pin wheel 51. The hammer arm 54 is fixed to a spindle 55 journalled in the frame, said spindle being provided with a crank arm 56 located below a pendant arm 57 rigid with the bell crank 40 so that as the arm 40^b is depressed during the initial movement of an hour strike the arm 57 acting through the crank arm 56 imparts a part rotary movement to the spindle 55 which moves the hammer pallet 53 relatively to the respective tooth 51^a so that the counting plate 33 can move slightly, due to the friction drive of the spring 39, immediately the peg 42 is withdrawn from the respective notch 43, such part rotary movement of the counting plate moving the notch out of register with the peg, the star wheel 51 also moving until the movement of the combined counting plate and star wheel are arrested due to the engagement of the tooth on the latter with the hammer pallet which has not been moved completely clear of the tooth.

When the lever 40 is released from the pressure 70 of the rocking lever 45, the spring 44 causes the lever arm 40^a to move towards the counting plate so that the peg 42, which bears on the face thereof, causes endwise movement of the counting plate element against pressure of the spring 39 until 75 said element is clutched to the continuously run-

ning gear wheel 35 so that rotary movement is imparted to the counting plate to move it until the peg 42 is in register with and enters the next notch 43 when the counting plate element is free to move endwise until it is declutched by the action of the spring 39.

The motion of the counting plate is imparted through multiplying gear 48, 49 to the hammer actuating pin wheel 51 and the movement of the hammer pallet 53 relatively to the pin wheel 51, 10 due to the crank arm 56, permits limited free movement of the gear at the commencement of the rotating movement of the pin wheel thereby obviating stress on the motor.

The hour striking mechanism can if desired be 15 set to act in correct sequence to the hour hand by depressing the rock lever 40^b manually until the number of strokes corresponds to the hour as indicated by the hands.

When the desideratum is a striking clock only, 20 no chiming barrel and associated mechanism is required, the counting plate being actuated in like manner to the previously described chiming barrel except that the arms to rock the clutch control lever 40^a are suitably modified so as to be 25 acted upon by means of a twelve-armed tappet wheel or star secured to the hour wheel one of the said twelve arms being longer than the eleven remaining arms thereof, a stop being provided on the counting plate 33 (Figures 3 and 6) the 30 said tappet wheel and stop jointly operating in like manner to the similar tappet wheel 23 and stop 29 formed upon the end face of drum 9 (Figures 2 and 4). It is to be understood that the self correcting mechanism for the hour strike, 35 may, if desired, be associated with the chiming clock described in the preceding example so that the hour striking mechanism is rendered self-correcting within the maximum period of twelve hours. The motion of the counting plate is 40 imparted through multiplying gear to the hammer actuating pin wheel as above described.

By these means electric clocks are provided wherein the chimes and/or strikes are effectively actuated without the necessity for racks, gathering pallets and snails or the like and attendant gearing, by the comparatively small synchronous electric motor which is also utilized to actuate the time hands in a sure and certain manner and wherein the parts are readily assembled.

Having now particularly described and ascertained the nature of my said invention and in what manner the same is to be performed, I declare that what I claim is:

1. An electric synchronous motor clock embodying visual and audible time-indicating mechanism comprising in combination an electric synchronous motor, visual time-indicating means and audible time-indicating means, constantly-meshing gear wheels to transmit motion to said visual and audible time-indicating means from the motor, separable clutch elements interposed in the constantly-meshing gear train to the audible time-indicating means, a member adapted to function as a counter to govern the extent of the audible time indications connected to and intermittently-rotated by the clutch, a spring-actuated member adapted to lock the counter in the stationary position and also to move the movable element of the clutch into operative engagement with the constantly-running element of the clutch, a spring normally tending to separate the clutch elements, and means actuated by the visual time-indicating mechanism to release the locking member, the arrangement being such that 75

the locking member maintains the clutch elements in operation to transmit motion to the counter until said counter is again arrested by said locking member.

3. 2. An electric synchronous motor clock embodying visual and audible time-indicating means comprising in combination an electric synchronous motor, visual and audible time-indicating means, a clutch having two separable elements, 10 constantly meshing gear wheels to transmit motion to the visual time-indicating means and also to one element of said clutch, a member adapted to function as a counter connected to the other and movable element of the clutch, a spring normally tending to separate the clutch elements, a 15 spring-actuated member normally tending to maintain the counter in the stationary position and also adapted to move the movable clutch element into engagement with the constantly-running clutch element when the locking member 20 has been released, and means actuated by the time-indicating mechanism to release the locking member.

3. An electric synchronous motor clock embodying visual and audible time-indicating mechanism comprising in combination an electric synchronous motor, visual time-indicating means, constantly meshing gear wheels to transmit motion to said visual time-indicating means, a 25 counter slidably and rotatably mounted on the frame and provided with a clutch element, a complementary clutch element driven by constantly-meshing gear wheels from the motor, a spring normally tending to separate the clutch elements, 30 a locking member to engage the counter and prevent rotation thereof, a member actuated by the time mechanism to move the locking member out of locking engagement with the drum, and means to cause said locking member to impart 35 sliding motion to the counter to cause the clutch elements to engage.

4. An electric synchronous motor clock embodying visual and audible time-indicating mechanism comprising in combination an electric synchronous motor, visual time-indicating means, constantly-meshing gear wheels to transmit motion to said time-indicating means, a chiming barrel slidably and rotatably mounted in the frame and provided with a clutch element, a 45 complementary clutch element continuously driven by constantly-meshing gear wheels from the motor, a spring-actuated locking member to engage the barrel and prevent rotation thereof, a member actuated by the time mechanism to move the locking member out of locking engagement with the barrel, spring means to cause the locking member to impart 50 sliding motion to the barrel to cause the clutch elements to engage, a spring normally tending to separate the clutch elements, 55 said chiming barrel and locking lever being provided with interengaging projections and recesses functioning as a counter.

5. An electric synchronous motor clock embodying visual and audible time-indicating mechanism comprising in combination an electric synchronous motor, visual time-indicating means, constantly meshing gear wheels to transmit motion to said time-indicating means, a chiming barrel slidably and rotatably mounted in the frame and provided with a clutch element normally held out of engagement with a complementary clutch element, a complementary clutch element continuously driven by constantly-meshing gear wheels from the motor, a spring- 65 actuated locking member to engage the barrel 70

and prevent rotation thereof, a member actuated by the time mechanism to move the locking member out of locking engagement with the barrel, spring means to cause the locking member to impart sliding motion to the drum to cause the clutch elements to engage, a spring normally tending to separate the clutch elements, the chiming barrel and locking lever being provided with interengaging projections and recesses to govern the period of chime, and means to positively arrest the turning movement of the drum when the locking member is released until the clutch elements engage. 5

6. An electric synchronous motor clock embodying minute and hour hand visual and also audible time-indicating mechanism comprising in combination an electric synchronous motor, visual time-indicating means, constantly meshing gear wheels to transmit motion to said time-indicating means, a chiming barrel slidably and rotatably mounted in the frame and provided with a clutch element normally held out of engagement with a complementary clutch element, a complementary clutch element continuously driven by constantly-meshing gear wheels from the motor, a spring-actuated locking member to engage the barrel and prevent rotation thereof, a member actuated by the time mechanism to move the locking member out of locking engagement with the barrel, spring means to cause the locking member to impart sliding motion to the barrel to effect engagement of the clutch elements, a spring normally tending to separate the clutch elements, the chiming barrel and locking lever being provided with interengaging projections and recesses to govern the period of chime, together with means to positively arrest the turning movement of the barrel when the locking member is released until the clutch elements engage, means to ensure that the cycle of movement of the barrel always corresponds in each hour to the cycle of movement of the minute hand. 15 20 25 30 35 40

7. An electric synchronous motor clock embodying minute and hour hand visual and also audible time-indicating mechanism comprising in combination an electric synchronous motor, visual time-indicating means, constantly-meshing gear wheels to transmit motion to said time-indicating means, a chiming barrel slidably and rotatably mounted in the frame and provided with a clutch element normally held out of engagement with a complementary clutch element, a complementary clutch element continuously driven by constantly-meshing gear wheels from the motor, a spring-actuated locking member to engage the barrel and prevent rotation thereof, a member actuated by the time mechanism to move the locking member out of locking engagement with the barrel, spring means to cause the locking member to impart sliding motion to the barrel to effect engagement of the clutch elements, a spring normally tending to separate the clutch elements, the chiming barrel and locking lever being provided with interengaging projections and recesses to govern the period of chime, together with means to positively arrest the turning movement of the barrel when the locking member is released until the clutch elements engage, automatic means to ensure that the cycle of movement of the drum always corresponds in each hour to the cycle of movement of the minute hand, a pin wheel and hour-striking hammer, a clutch to impart intermittent movement to the pin wheel, constantly-meshing gear wheels to im- 50 55 60 65 70 75 80 85 90 95 98

part continuous rotary motion to one element of the clutch, a counter associated with the movable element of the clutch, a spring-actuated locking member to engage the counter and prevent rotation thereof, a member actuated by the chime barrel to move the locking member out of locking engagement with the hour strike counter,

spring means to cause the locking member to impart sliding motion to said counter to effect engagement with the clutch elements and a spring normally tending to separate said clutch elements.

FRANK DAVENALL NORTON.
